FIG. 5.

Patented Mar. 19, 1929.

UNITED STATES PATENT OFFICE.

GEORGE AUSTIN, OF KANSAS CITY, MISSOURI.

WELL SCREEN.

Application filed April 30, 1928. Serial No. 274,019.

This invention relates to concrete screens for water wells, and has for its object the provision of an efficient screen of large water capacity, which utilizes the flow of water in the charging of the well to prevent the entrance of sand into the well; a further object being to provide a wall upon each section composing the screen, to cooperate in the sand-excluding action, and a groove in the bottom of each section above the adjacent wall, to give free and unobstructed passage to the water entering the well through the screen and over the adjacent underlying wall.

With these and other objects in view, the invention consists in certain novel and useful features of construction and combinations of parts as hereinafter described and claimed; and in order that it may be fully understood reference is to be had to the accompanying drawing, in which:

Figure 1 is a side elevation of a well screen embodying the invention.

Figure 2 is a top plan view of the same.

Figure 3 is an enlarged fragmentary view, partly in side elevation and partly in central vertical section of the well screen.

Figure 4 is a fragmentary perspective view of one of the well screen sections as viewed from above.

Figure 5 is a similar view of one of the sections as viewed from below.

Figure 6 is a fragmentary side elevation of a well screen section of slightly modified construction.

Figure 7 is a fragmentary perspective view of a section of the modified type, as viewed from below.

Figure 8 is a vertical section through two sections containing the water-way grooves of the type shown in Figures 6 and 7.

In the said drawing the well screen is shown as composed of any suitable number of concrete sections of ring-form, arranged in superimposed relation.

Each section is provided at the upper and lower ends of its periphery with outwardly-projecting flanges 2 and 3 respectively, to serve as treads in rolling a section upon the ground with the least chance of its being chipped or suffering other injury when moved in the manner indicated from one point to another.

In the outer side of the peripheral surface of each section, there are provided at suitable distances apart, vertical grooves 4, extending from the bottom of the flange 2 to and

through the flange 3, these groove receiving water entering the well-hole within which the screen is erected, and the bottoms of said grooves preferably slope downwardly and outwardly as indicated at 5, for a purpose which hereinafter appears.

Each screen section is provided at its upper side with an upstanding circular wall 6, and in its bottom in the vertical plane of wall 6, with a circular groove 7. Each section is also provided inward of groove 7 with a series of depending lugs 8, adapted in the assembly to rest upon the underlying section within the wall 6 thereof, and hence provide a space between the sections, the space being unbroken except where interrupted by said lugs.

It is preferred to employ about eight of the lugs mentioned, and every alternate lug is provided with a vertical passage 9 which is continued up through the section. Extending through said passages are cables 10 or the like, the sections being successively strung upon the cables when the former are about to be lowered to position in the well-hole, it being understood that below the undermost section the cables will, as customary, be so arranged or equipped as to guard against them sliding up through and becoming disconnected from the undermost section.

The wall 6 occupying a circle outside that within which the lugs lie, cooperate with the latter in centering the sections, it being obvious however that where a plurality of cables are employed, they can be depended upon for the centering of the sections. Where the cables are not employed the cooperative centering section of the wall and lugs, is desirable.

It will be understood that the well-hole is of greater diameter than the sections and that the space between the sections and the wall of the hole will be charged with any suitable filtering material, not shown, such as gravel or the like, so as to minimize to the fullest extent, the possibility of clay, fine sand or other material clogging the water passages 4 and the spaces between juxtaposed sections.

The sections will be sufficient in number to extend from below to a point slightly above the water bearing strata of the ground, and the water entering the well-hole will pass into the screen through the spaces between the sections. In this passage, any fine sand with which the water is charged will be intercepted

by the walls 6 and lodge upon the sections exterior to said walls, which it will be noted by reference to Figure 3, project slightly into the grooves 7 of the overlying sections and 5 slightly above the plane of the lower faces of such sections at their outer margins. The water therefore is free to flow over said walls into the grooves 7, and then pass downward on the inner side of the walls and into the 10 screen between the lugs 8 thereof.

To increase the capacity of the well screen by providing for a more unimpeded flow of water, the sections are provided with the vertical passages 4. The water entering such 15 passages, flows downward and by impingement on the deflecting portions 5 of the bottoms of said grooves, is deflected outwardly and tends to dislodge sand which may have collected upon the underlying sections outward of the walls 6 thereof, which action obviously guards against the clogging by sand or the like of the spaces between the sections and the consequent exclusion of water from passing inwardly between the sections.

25 To make provision for accommodating the free entrance of water into and down through the external grooves of the sections, it is desirable under conditions where the water supply is good, to gradually increase the cross 30 sectional area of said external grooves toward the bottom or discharge end thereof without increasing the width of the mouths of said grooves as at 4^a in Figures 6, 7 and 8. It is considered that a simple way to accomplish 35 this result most effectively is to have the side walls of the grooves diverge inwardly of the section from the parallel edges of the mouths of the slots, and it may also be desirable to have the bottoms of the slots slope downward 40 and inward and thus cooperate with the diverging side walls, in providing grooves which gradually increase in cross section from the top toward the bottom. With a groove of the character described, it will be apparent 45 that its capacity is such as to accommodate a continual inflow of water for the full length of the groove which would not be possible were the grooves of uniform size. The modified form of groove is preferable it is believed 50 where the supply of water is plentiful, al-

though it is fully as effective as a groove of uniform cross-sectional capacity, where the supply of water is not sufficient to require grooves of increasingly larger capacity toward their lower ends.

55 From the above description, it will be apparent that I have produced a well screen embodying the features of advantage set forth as desirable in the statement of the objects of the invention, and while I have illustrated and described the preferred embodiments of the invention, it will be apparent that it is susceptible of modification in minor particulars without departing from the spirit and scope of the appended claims.

60 I claim:

1. A well screen comprising a series of superimposed ring sections providing intervening spaces, each section having a plurality of depending lugs resting on the adjacent underlying section and an annular bottom groove intermediate said lugs and the peripheral margin of the section, and each section having an upstanding wall occupying the same vertical plane as and projecting up into the groove of the overlying section and also having vertical grooves in the periphery extending from the bottom of the section to a plane below the top of such section, said grooves having downwardly and outwardly 75 sloping deflector surfaces extending to the plane of the bottom of the respective sections.

2. A well screen comprising a series of superimposed ring sections providing intervening spaces, each section having a plurality of depending lugs resting on the adjacent underlying section and an annular bottom groove intermediate said lugs and the peripheral margin of the section, and each section having an upstanding wall occupying the same vertical plane as and projecting up into the groove of the overlying section and also having vertical grooves in the periphery extending from the bottom of the section to a plane below the top of such section; said 80 grooves increasing in cross-sectional area toward their lower ends.

95 In testimony whereof I affix my signature.

GEORGE AUSTIN.
